Des. 175,644
Patented Sept. 20, 1955

175,644

MASKING UNIT FOR BOWLING ALLEY PINSETTERS OR THE LIKE

Richard G. Reineman, Muskegon, Mich., assignor to The Brunswick-Balke-Collender Company, a corporation of Delaware

Application January 10, 1955, Serial No. 33,913

Term of patent 14 years

(Cl. D34—5)

Fig. 1

Fig. 3

Fig. 1 is a perspective view of a masking unit for bowling alley pinsetters or the like, showing my new design;

Fig. 2 is a front elevation thereof; and

Fig. 3 is a side elevation thereof.

The dominant features of my new design are shown in solid lines in the drawing.

I claim:

The ornamental design for a masking unit for bowling alley pinsetters or the like, as shown and described.
